WINDOW CONSTRUCTION

Harry M. McKay, Winfield, Kans.

Application April 18, 1949, Serial No. 88,100

2 Claims. (Cl. 20—52.2)

1

This invention relates to a new and useful construction in which a window sash is slidably mounted in a frame. As is well known, it is desirable for the sash to slide easily in its frame to facilitate the opening and closing of the window. It is also necessary that some means be provided for maintaining the sash in whatever position of elevation it may be placed. This is commonly done at present by attaching an end of a sash cord to one edge of the sash, running the cord over a pulley mounted near the upper end of the window frame, and attaching the other end of the sash cord to a weight capable of balancing the weight of the sash, the weight being enclosed in a casing built into the side of the frame. This construction involves considerable labor time and is therefore relatively expensive.

It is an object of this invention to provide a sash which fits a standard window frame, which employs friction to maintain it at any desired position of elevation, and which therefore eliminates the necessity of using the conventional sash cords and weights. Naturally the construction also eliminates the labor and material ordinarily required to provide a weight or balance casing at the sides of the window frame to accommodate the counterbalancing weights.

It is another object to provide a sash which may be easily and quickly installed in or removed from a standard window frame after the frame has been completed, without having to remove or replace either the blind stop, the parting stop, or the interior molding of the frame.

It is still another object of the invention to provide a sash which is so constructed as to compensate for the normal expansion and contraction in overall width due to outside weather conditions, thus eliminating "sticking" of the sash in its frame due to an extreme increase in friction against the jambs of the frame.

Another important object of the invention is to provide an attachment capable of converting any conventional wooden sash into a sash of the type mentioned above, so that it can be replaced in its original frame without the necessity of modifying the frame in any way, and without the necessity of using the balancing weights with which the sash was originally provided.

Another object is to provide a sash having the characteristics mentioned above, and which is also capable of being installed with or without weather stripping.

Generally the invention comprises an elongated hollow trough, preferably of thin sheet metal, of such size and shape as to telescopically

2

receive and fit over one side edge of a window sash after a portion of its extreme side edge has been removed. The trough then fits into the channel of the window frame, and the trough is pressed outwardly against the jamb of the frame by means of springs bearing against the sash proper and against the inside surface of the trough, the friction created by the spring pressure being ample to maintain the sash in any position of vertical adjustment in its frame.

The details of construction of a preferred embodiment of the invention, together with other objects attending its production, will be more clearly understood when the following description is read in connection with the accompanying drawings, in which:

Fig. 1 is a perspective view of a sash embodying one form of the invention;

Fig. 2 is a fragmentary sectional view taken vertically through the right hand side of the sash of Fig. 1;

Fig. 3 is an enlarged sectional view taken along the line 3—3 of Fig. 2; and

Fig. 4 is a fragmentary horizontal sectional view through one vertical side of a complete window showing details of construction and installation of sashes embodying the invention in a different form.

Referring to that form of the invention illustrated in Figs. 1—3 inclusive, the numeral 10 designates a window sash as a whole, made up of parallel side members 11 and 12, and parallel top and bottom members 13 and 14, all connected together at their ends to form a frame for receiving and holding a pane 15. The side member 12 is preferably somewhat narrower than the other members, and is adapted to fit snugly into a sheet metal trough permitting telescopic movement of said trough with relation to the sash. The trough is designated as a whole by the numeral 16, and is made up of two parallel sides 17 and 18, two parallel ends 19 and 20, and an integral bottom 21.

Interiorly the trough 16 carries a plurality of metal guides 22. These guides preferably have a substantially cylindrical body 23, an enlarged flange type head 24 which is welded or otherwise rigidly secured to the inner surface of the bottom 21, and a spring receiving reduced end 25. Each guide has a small central bore to slidably fit the shank of a screw 26, and a connecting enlarged bore 27 to receive and permit sliding movement of the head of the screw. The trough bottom 21 is provided with apertures 28 which are aligned with the respective bores 27

to permit insertion of the screw from the outside of the trough.

The sash side member 12 is provided with a plurality of properly spaced drilled blind holes 29, one for snugly but slidably receiving a respective one of the guides 22.

In installing a trough, such as described, on each window sash a compression spring 30 is first inserted into each blind hole 29. The guides are then inserted into these holes and the walls of the trough simultaneously slip over the side member of the sash. The screws 26 are then driven into side member of the sash, as shown in Figs. 2 and 3, with the springs 30 slightly compressed. For appearance sake only the distance between the trough bottom 21 and the inner edge of the side member 12 should be approximately the same as the distance between the corresponding outer and inner edges of the side member 11, when the sash is installed in a window frame.

Installation is accomplished by first inserting the trough into the vertical slide channel of a window frame with the bottom of the trough in contact with the jamb 31 of the window, as shown in Fig. 4. The entire sash is then forced toward the jamb 31, compressing the springs 30 a sufficient distance to allow the other side member 11 of the sash to clear its vertical stop 32 at the other side of the window frame. The sash is then released to the action of springs 30, and the side member 11 enters its complementary vertical slide channel at the other side of the window frame. The springs 30 are of such length, and have such compressibility characteristics that the pressure of the trough bottom 21 against the jamb 31 is not great, but is ample to create sufficient friction between these two members to maintain the sash in any position of elevation to which it is manually moved. Thus weights for counterbalancing the weight of the sash are completely eliminated.

It will be noted that the screws 26 are of such length that their heads clear the adjacent shoulders of the blind holes 29 when the sash is installed in a window frame. This spacing permits free action of the springs 30, and sufficient movement of the side member 12 with relation to the trough to compensate for overall contraction or expansion in the width of the sash as a whole, due to changing temperature or moisture conditions.

The embodiment of the invention illustrated in Fig. 4 differs from the embodiment just described in one respect only. The adjacent side walls 33 and 34 of each of the troughs 16 have reversely turned flanges 35 and 36, respectively, lying in planes substantially parallel to the side walls 33 and 34 proper, and spaced therefrom a sufficient distance to snugly but slidably receive flanges 37 and 38 which are formed as an integral part of a formed metal parting stop, designated as a whole by the numeral 39. This parting stop 39 is substantially W-shaped in cross section and extends from top to bottom of the window frame. It is anchored to the jamb 31 by a plurality of vertically spaced screws 40. The interlocking of the flanges 35 and 36 with the flanges 37 and 38 form a weathertight joint between the sash and

its frame—a joint which permits free sliding of the sash.

Having described the invention with sufficient clarity to enable those familiar with the art to construct and use it, I claim:

1. A friction type sash balance and variable lateral extension for a window sash comprising a trough having parallel ends, parallel sides and a bottom, and of a size to complementally and telescopically receive and enclose one side edge of the sash; a plurality of longitudinally spaced axially bored and counter bored elongated guides projecting inwardly from and rigidly secured to the bottom of said trough perpendicular thereto, the counter bores being located adjacent said bottom; holes in said bottom aligned with said counterbores; cooperating seats in the side edge of said sash for complementally and slidably receiving said guides; compression coil springs housed in said seats and bearing outwardly against the inner ends of said guides; and screws passing axially through the guides, through the springs and anchored in the side edge of said sash, the heads of said screws being of larger diameter than the smaller bores in said guides, and seated in the counter bores thereof to limit outward spring pressed movement of said guides and consequently of said trough, the relative depth of the seats in said sash being such that the overall width of the sash, when the trough is fully telescoped over said one side edge, is less than the width of the fixed window frame in which the sash is adapted to be slidably mounted, whereby the sash can be easily installed in and removed from the window frame.

2. A friction type sash balance and variable lateral extension for a window sash comprising: a trough having parallel ends, parallel sides and a bottom, and of a size to complementally and telescopically receive and enclose one side edge of the sash; a plurality of longitudinally spaced guide receiving slideways cut into said one side edge of the sash at right angles thereto; similarly spaced guides each having an end secured to the inner surface of the bottom of said trough, and adapted to be received into and guided by said slideways; a spring in each slideway bearing against the adjacent end of each guide to urge the guides and the attached trough outward with relation to the sash; and means fixed to the sash and slidably connected to each guide to limit the outward movement thereof with relation to its respective slideway.
